MULTIPLE CHAIN LADDER

Noël L. Dahlander, New York, N. Y., assignor of
two-fifths to Robert J. Earl, New Canaan,
Conn.

Application June 18, 1942, Serial No. 447,529

20 Claims. (Cl. 228—40)

This invention relates to chain ladders in general and more especially to multiple chain ladders suitable for descending from dirigibles or buildings in case of an emergency or for some other reason or for disembarking passengers and troops from seagoing vessels, transports and the like in the case of an emergency or for some other reason.

Among the objects of the present invention, it is aimed to provide an improved multiple chain ladder suitable for descending from dirigibles, buildings and the like in case of an emergency or for some other reason or for disembarking passengers and troops from seagoing vessels, transports and the like in the case of an emergency or for some other reason.

It is also an object of the present invention to provide an improved multiple chain ladder which can be folded or rolled up readily in the interests of conserving space when packed away out of use to which end a plurality of sets of ladder rungs are mounted on chains in which the rungs are staggered relative to one another to facilitate rolling or folding up the multiple chain ladder and to conserve space.

It is still another object of the present invention to provide an improved means for spacing a multiple chain ladder from the outer surface of the hull of the vessel which will not only protect the user from having his hands and feet injured while climbing on the same but also serve as an electric insulator to prevent the formation of sparks should the chains strike the outer surface of the hull of the vessel to thereby in turn reduce to a minimum the fire hazard resulting from such formation of sparks and the consequent danger to a cargo of inflammable material such for instance as petroleum, gasoline and the like.

It is still another object of the present invention to provide an improved ladder rung and particularly the means for connecting the rung to the intervening chain elements which will enable reducing the cost of materials and the cost of labor for assembly to a minimum.

It is still another object of the present invention to provide an improved multiple chain ladder and particularly of forming the means for spacing the ladder from the outer surface of the hull of the vessel and also of forming the rungs of the ladder of some suitable buoyant substance, such as wood and the like whereby the multiple chain ladder when accidentally thrown into the water will not disappear to the bottom with the danger of being lost but maintain the entire ladder afloat until recovered, and also in an emergency, to a certain extent, supplement a life saving raft or even serve as a substitute for a life saving raft.

It is also an object of the present invention

to provide an improved collapsible bracket which in extended position will enable a chain ladder to be spaced from the outer surface of the hull of the vessel and also facilitate cooperation with the railing to permit rolling or folding up the chain ladder on the deck of the vessel when out of use.

It is still a further object of the present invention to provide a multiple chain ladder including means for quickly suspending the ladder into suspended position for use in case of an emergency and also for facilitating the rolling or folding up of the ladder when the same is packed up out of use.

These and other features capabilities and advantages of the invention will appear from the subjoined detail description of specific embodiments thereof illustrated in the accompanying drawings in which

Fig. 1 is a fragmental front elevation of a multiple chain ladder in suspended position made according to one embodiment.

Fig. 2 is an enlarged fragmental front elevation of a corner of the multiple chain ladder in suspended position shown in Fig. 1.

Fig. 3 is a fragmental detail in front elevation on a larger scale than that shown in Fig. 2 showing the connection between a chain link and a rung.

Fig. 4 is a section on the line 4—4 of Fig. 3.

Fig. 5 is a fragmental detail in front elevation of a modification on the scale shown in Fig. 3 of the connection between a chain link and a rung.

Fig. 6 is a fragmental plan of the modification shown in Fig. 5 partly in section on the line 6—6 of Fig. 5.

Fig. 7 is a fragmental detail of still another modification on the scale shown in Fig. 3 of the connection between a chain link and a rung.

Fig. 8 is an end elevation of the detail shown in Fig. 7.

Fig. 9 is a front elevation of a spacer on the scale shown in Fig. 2.

Fig. 10 is a section on the line 10—10 of Fig. 9.

Fig. 11 is a front elevation of a portion of another form of spacer on the scale shown in Fig. 9.

Fig. 12 is a section on the line 12—12 of Fig. 11.

Fig. 13 is a front elevation partly in diagrammatic form in suspended position on the scale in Fig. 1 of a multiple chain ladder equipped with means to facilitate rolling up the same.

Fig. 14 is an end elevation of the embodiment shown in Fig. 13.

Fig. 15 is an end elevation of another embodiment whereby the chain ladder may be collapsed, that is faked or flaked together in packing.

Fig. 16 is a fragmental front elevation of still another form of connection between a chain and a rung on a slightly smaller scale than that shown in Fig. 3.

Fig. 17 is an end elevation of the embodiment shown in Fig. 16.

Fig. 18 is an end elevation of the spacer disk used in the embodiment of Fig. 16.

Fig. 19 is a perspective on the scale of Fig. 16 showing the connection between a chain and a guiding link for the rope or lanyard for rolling or folding up the multiple chain ladder shown in Fig. 13.

Fig. 20 is an end elevation partly in section of a bracket associated with a multiple chain ladder and the railing of a vessel.

In the embodiment shown in Figs. 1, 2, 3, 4, 9 and 10, there is illustrated a multiple chain ladder which is composed of a plurality of longitudinally extending chains 2 which in turn are connected near their upper ends by the transversely extending chain 3. The chains 2 are connected to the chain 3 at intervals of about 12 inches from one another. When the links of which the chains 2 and 3 are composed, are of the type generally known as the "Lock Link" type, as shown particularly in Fig. 2, then the chain 3 alternately passes over and under the successive longitudinally extending chains 2, with the loop 4 of the chain 3 as an instance passing over the loop 5 of the chain 2, the loop 6 of the chain passing under the loop 7 of the next succeeding chain 2, and the loop 8 passing over the loop 9 of the next succeeding chain 2. The loops 4, 6 and 8 cross the loops 5, 7 and 9 respectively where they are anchored to one another as shown in my co-pending application for patent executed on or about June 6, 1942, Serial No. 446,485, that is by means of four rings for each connection. Since the several connections are identical, the one for connecting the loops 4 and 5 alone will be described. The ring 10 passes over the shank portion 11 of the loop 4 and under the shank portion 12 of the loop 5, and ring 13 passes over the shank portion 11 of the loop 4 and under the shank portion 14 of the loop 5, the ring 15 passes over the shank portion 16 of the loop 4 and under the shank portion 14 of the loop 5, and the ring 17 passes over the shank portion 16 of the loop 4 and under the shank portion 12 of the loop 5. Obviously other connecting means could be used such as shown in my co-pending application above referred to without departing from the general spirit of the invention herein disclosed.

The upper free end of each chain 2 is connected by a rivet to an inverted link of the "Lock Link" type, in which case the link 171, as an instance, has its looped ends 18 and 19 spread apart to receive and register with the looped ends 20 of the link including the loop 5, and thereupon in turn to receive the rivet 21 in the usual way. The link 171 preferably has a shield or thimble 22 formed along a part of its inner periphery as a wear receiving surface to engage the ring 23. The upper ends of each of the remaining chains 2 are preferably similarly connected to lash receiving rings such as the ring 23, but since these connections and rings are substantially identical, it will be unnecessary to repeat the aforesaid description with regard to each of the rings bearing the reference character 24 in Fig. 1.

The ladder rungs 25 in this embodiment are preferably composed of a main bar 26 composed

as an instance of wood, of about 12 inches in length and provided with metal clips 27 and 28 one at each end, see Figs. 3 and 4. The wood bars 26 are preferably rectangular in cross section with the corners rounded off as shown, the rectangular cross section facilitating a firm grip by the user, and the rounded corners in turn eliminating any sharp edges that might injure the hand of the user when engaging the rungs in the use thereof.

To serve not only as a reinforcement for the rungs against splitting when composed of a substance such as wood, and also to cooperate with the links of the chains 2 to prevent the metal of the chains 2 cutting into the ends of the rungs 26 with wear, the metal rings 29 are provided which are fitted into the circular recesses at the ends of the bars 26. Each of the clips, see the clip 28, consists essentially of two securing flanges 30 and 31 which extend laterally along the sides of the bar 26 over the ring 29 and has a grooved extension 32. The flanges 30 and 31 preferably have two screws 33 and 34 extending from one flange 30, through the bar 26 into screw threaded connection with the other flange 31 as shown, in which case the heads 35 and 36 are countersunk, and the screw threaded ends 37 and 38 are buried as shown, so that the threads are fixed against displacement.

The grooved extension 32, as particularly shown in Figs. 3 and 4, pivotally receives the shank portion 39 of the link 40 in which case the shank portion 39 composed of metal will be engaged by the ring 29 of the curved extension 32 of the metal clip 28 to protect the end of the wooden bar 26 from wear.

The rungs between any two successive chains 2 are spaced about 12 to 14 inches from one to the other, with the rungs 26 between any set of successive chains, constituting one set of rungs in staggered relation to the next succeeding set of rungs and so on. In the present instance, however, the alternate sets of rungs, see Fig. 1, are in alignment with one another. This arrangement of the rungs contributes materially to the flexibility and adaptability of the multiple chain ladder for folding or rolling the same when not in use.

Another form of connection between a rung and chain is shown in the embodiment illustrated in Figs. 5 and 6, in which the bar 41 again is preferably composed of wood and rectangular in cross section but with rounded corners, as shown, and the end portion rounded and threaded to receive the cylindrical metal portion 43 of the ferrule 44 having the extension 45 provided with a loop 46 at the end thereof, see Fig. 6, pivotally to receive the shank portion 47 of the link 48, the portion 43 being first screw threadedly connected to the rounded end of the bar 41 by the threads 48 and then secured against unscrewing by the pin 44.

In the embodiment shown in Figs. 7 and 8 there is illustrated another form of connection between a rung and chain particularly suited for a rung 49 composed of cylindrical metal stock such as shown having diametrically opposed slits 50 and 51 at the ends thereof to receive links such as the link 52 against turning with the free end thereof extending through the metal disk 53 and riveted or spun over to anchor the disk 53 in place in which case the disk 53 not only serves to anchor the link 52 in place but also serves as a spacer to space the rungs from the side of the vessel in order to protect the hands of the

user against injury should be chain swing toward the side of the vessel while in use.

In the embodiment shown in Figs. 1, 2, 9 and 10, instead of the metal disks such as the disks 53, serving as spacers, there are provided the split wooden blocks or spools 54 each composed of two semi-cylindrical complementary halves 55 and 56 having central recesses 57 and 58 which register with one another to form a central opening for the composite block 54 to receive a link, such as the link 59 of a chain 2. The two complementary halves 55 and 56 are preferably connected to one another by two screws 60 and 61, the heads 62 of which fit into the recesses 53 and the nuts 64 of which are screw threaded into place in the recesses 55.

In Figs. 11 and 12, another type of wooden spacer block is shown, see the block 65 the complementary halves 67 and 68 of which are connected by two screws 69 and 70 which in this instance extend through a link, such as the link 71 of the chain 2 as shown, instead of being embedded in the wood to either side of the chain 2, as shown in the embodiment of Figs. 9 and 10. Here also the heads 67 and 68 of the screws 69 and 70 respectively are both positioned in one and the same recess 71 and the nuts 69 and 70 are screw threaded in place on the screws 69 and 70 respectively in one and the same recess 71.

With spacer blocks such as the blocks 54 shown in Figs. 9 and 10 and such as the blocks 65 shown in Figs. 11 and 12, the chain 1 is provided with an electric insulator to intervene between the chain and the side of the vessel so as to prevent the formation of sparks as an instance when the chain 1 is swung against the vessel as the result of rough water or a storm. The value of such insulation especially when the vessel is an oil tanker is of course obvious.

Furthermore, when the rungs 25 are composed of wood and supplemented by the spacers 54 or 65, also composed of wood, sufficient buoyancy is ordinarily afforded to the chain should it fall into the water accidentally thereby to prevent it from dropping down to the bed of the water.

In actual practice, excellent results have been achieved when the spacers such as the spacers 54, see Fig. 1, are mounted on every other chain 2, with one set, as an instance, the blocks 78, placed two feet below the rings 24 and on the third, seventh and eleventh chains designated 2, counting from the right. The next set of blocks 54, as an instance, the set 79, are staggered relative to the blocks 78 being positioned on the first, fifth and ninth chains designated 2 counting from the right, this set 79 being spaced about one foot down from the level of the blocks 78.

It will be desirable to provide the chain 1 with additional blocks 54, as an instance the blocks 80 mounted farther down as an instance at least three feet below the level of the blocks 78, which blocks 80 would again preferably be mounted on the third, seventh and eleventh chains counting from the right just as is the case with the blocks 78.

The next set of blocks 54, as an instance the blocks 81, would be placed on the first, fifth and ninth chains 2 counting from the right, and preferably about two feet below the level of the blocks 80, and if the multiple chain 1 extended down beyond the level of the blocks 81, then at intervals of about three feet there would be disposed additional sets of one or more rows of blocks such as the sets 78 and 79, and the sets 80 and 81. In the embodiment shown in Figs. 13 and 14

there is illustrated another form of multiple chain ladder designated 82. The arrangement of the longitudinally extending chains 83 and the rungs 25 is substantially identical to that of the chains 2 and rungs 25 respectively of the embodiment illustrated in Fig. 1. This embodiment is different in the arrangement of the spacer blocks 84 and in the addition of booms or poles such as the poles 86, 87, 88 and 89. The first pole 86 is preferably positioned two feet below the border chain 88 at the top of the ladder 82, the next pole 87 is positioned about ten feet below the pole 86, the pole 88 about ten feet still lower down, and the pole 89 in the present instance at the lower end of the multiple chain ladder 82. These poles 86, 87, 88 and 89, may be made of metal but preferably are composed of some suitable buoyant material such as wood and of about three inches in diameter. The poles 86, 87 and 88 preferably have eyelets 91 formed thereon to be interlocked with links of the longitudinally extending chains 83, with the poles located on the rear side of the multiple chain ladder 82 so that they may not only serve as positioning means for the chains 83 and to maintain the chains 83 spread out relative to one another but also serve as a spacer medium to space the ladder 82 from the side of the vessel and thereby protect the hands of the users. When serving as spacers the poles 86, 87 and 88 and also the pole 89 may supplement the blocks 54 and also the special metal spacer disks 52 such as shown in Figs. 16, 17 and 18. The pivotal connections of the chains 83 in the loops 82 can still be used to advantage when the booms or poles 86 to 89 are used to compensate for the swaying or rolling of a vessel, these pivotal connections nevertheless permitting slight pivotal motion at these points and thereby protecting the chain links from the excessive shearing force that would otherwise be transmitted to the links connected to the rungs, if no such pivotal movement were permitted. However, when the multiple ladders are used at the stern or bow of a vessel in order to compensate for the curvature generally there present, the booms and poles will be omitted to enable the ladder freely to bend in the loops 82 to conform to the curvature of the vessel.

The blocks 54 when used with the poles 86 to 88 are preferably spaced from one another and staggered as shown. As an instance the upper row of blocks 83 would be disposed about two feet above the pole 87 and mounted on the second, sixth and tenth chains 83 counting from the right, the next lower row of blocks 84 might be positioned as close as one foot below the pole 87 and mounted on the fourth and eighth chains 83 counting from the right, the next lower row of blocks 85 positioned at a level three feet above the pole 88 and mounted on the second, sixth and tenth chains 83 counting from the right, the next lower row of blocks 86 positioned at a level one foot above the pole 89 and mounted on the fourth and eighth chains 83 counting from the right, and the next lowermost row of spacers 87 disposed about one foot below the pole 89 and mounted on the second, sixth and tenth chains 83 counting from the right.

The lowermost pole 89 is preferably provided with two sets of eyelets, one set of eyelets 92 to receive links at the lower ends of the chains 83, and another set of eyelets 93 to receive the lanyards or drag ropes 100 having floats 101 at intervals of five to ten feet. These lanyards may

be composed of ordinary hemp and be as long as fifty feet, and the floats 101 preferably are composed of some suitable buoyant material such as wood, and spherical in form and about two and one-half inches in diameter. Furthermore these lanyards 100 by the aid of the floats 101 are intended to ride on the surface of the water at the end of the ladder 82 to serve as life saving ropes for the users of the ladder should any of them fall into the water. Furthermore the poles 86 to 89, inclusive, the spacers 85 and the floats 101 will cooperate to aid in preventing the ladder from dropping down to the bed of the sea, should it accidentally be released, and aid in maintaining the same afloat long enough to enable a member of the crew to retrieve it.

When a pole is secured to the lower ends of the chains 83, as an instance, the pole 89, it will materially aid in cooperating with a halyard such as the rope 102 shown in Figs. 13 and 14 to enable rolling up the ladder 82 into a compact package for storage on the deck or other place. In such case, the halyard 102 is anchored at one end as an instance by the pin 103 or other suitable securing means to the side of the vessel, the halyard 102 then wrapped around the pole 89 two or three turns and the other free end secured to the deck of the vessel where it can be readily grasped for manipulation of the pole 89. The wrappings 104 of the halyard 102 are preferably made around the portion of the pole 89 extending beyond the outer longitudinally extending chain 83. Preferably also both free ends of the pole 89 are so equipped with halyards such as the halyard 102. Thereupon at the appointed time, when it is desired to roll up the chain 82 the free ends 105 of the halyards 102 at both ends of the ladder 82 will be grasped and pulled upwardly whereby in turn the pole 89 will rotate and at the same time wrap the chain 82 around it as the pole 89 is raised.

In order to maintain the halyard 102 adjacent to an outer free edge of the ladder 82, and to guide the halyard 102 the portion of the halyard 102 between the pin 103 and the pole 89 will extend through the loops of the links 106 preferably of the "Lock Link" type connected by a rivet 107, see Fig. 19, to a link 108 of the outer chain 83 of the ladder 82. In order to connect the link 106 to the link 108 its looped ends are spread apart to receive the link 108 between them whereupon a rivet 107 is passed through the looped ends 106 and the link 108 as shown in Fig. 19 and secured in place in the usual way.

In some instances it may be desirable not to roll up the ladder 82 but merely to fanfold it or flake it, in which case a single length halyard 109, see Fig. 15, is connected to a free end of the lower pole 110 and such halyard 109 extend upwardly through links 111, such as the links 106 shown in Fig. 8. In this case when it is desired to fanfold or flake the ladder shown in Fig. 15 it is only necessary for the member of the crew to engage the free end 112 and draw upwardly on the same to elevate the pole 110 and thereby simultaneously fanfold or flake the rest of the ladder into folded or packed condition.

When it is desired to use the spacer disks 92 shown in Figs. 16, 17 and 18, the rungs 84, as an instance the rung 113, may nevertheless be composed of some suitable buoyant material such as wood, the disk formed of metal and cooperate with a metal clip 114 now to be described. The disks 92 in the present instance are disposed at the opposite ends of rung 113 and have a diam-

eter considerably greater than that of the rung 113. The rung 113 may be course be rectangular in cross section as is the case with the rungs 26 and 41 illustrated in Figs. 4 and 5 respectively or else be cylindrical as shown in Figs. 16 and 17. When cylindrical, the disk 92 has two flanges 115 and 116 bent inwardly, and curved and spaced from one another to intimately engage the rung 113. In addition, see Fig. 18, the disk 92 is provided with two curved slots 117 and 118 to receive the parallel arms 119 of the clip 114 which extend through the openings 117 and 118 and then engage the outer opposite faces of the rung 113 and are there secured in place by suitable pins or screws 120 and 121. The clip 114 has a looped end 122 extending from the free end of the rung 113 and outside of the disk 92 as shown in Fig. 16 pivotally to receive a shank portion 123 of the adjacent link 124 of the adjacent chain 83.

In view of the foregoing it will thus appear that when the rungs 84, the spacers 85, the poles 86 to 89 inclusive and the floats 101 are all composed of some suitable buoyant material such as wood, they will very effectively cooperate with one another to maintain the ladder 82 afloat until retrieved should it accidentally be released. Furthermore to a limited extent it may also serve as a life raft in case of an emergency.

In some instances in addition to the spacers 30 54 shown in Fig. 1 or the spacers 66 shown in Fig. 11 or the spacers 85 and 92 shown in Fig. 13, a bracket such as illustrated in Fig. 20 may be provided. This bracket may consist of an arm 125, or a plurality of arms 125 pivoted to the side plate 126 of the vessel adjacent the uprights 127 of the railing 128. The outer end of each of such arms 125 is pivotally connected to a bar or link 129 having a hooked or crooked end 130. These bars 125 and 129 may be folded up to the dotted line position shown in Fig. 20 when out of use, or disposed in extended position, the full line position, with the crook 130 engaging the rod 131 of the railing 128. A multiple chain ladder 132 such as the chain ladder shown in Fig. 1 45 as an instance is provided with a plurality of rings such as the rings 133 at the upper end thereof which are lashed to the railing 128 by the lanyards or lashings 134. When the multiple chain ladder 132 is stored on deck it is rolled up into the roll 135 shown in dot and dash lines in Fig. 20. If on the other hand the ladder 132 is to be extended in use, the sets of arms 125 and 129 are first extended into the full line position shown in Fig. 20 and then the ladder 132 swung 50 over the railing 128 to engage the bar 136 forming the pivot point of a plurality of arms 125 and 129, in turn to be spaced from the side 137 of the vessel as shown in Fig. 20.

It is obvious that various changes and modifications may be made to the details of construction without departing from the general spirit of the invention as set forth in the appended claims.

I claim:

1. The combination of a plurality of longitudinally extending suspensory members having chain links including longitudinally extending shank portions, a plurality of rigid rungs, and means for pivotally connecting the ends of the rungs to shank portions of adjacent chain links to form a plurality of adjacent longitudinally extending ladders, said connecting means each including a metal clip engaging the sides of a rung adjacent each end thereof, the clip also having a loop formed adjacent the free end of a rung to receive

a shank portion of a link of one of said longitudinally extending chains.

2. The combination of a plurality of longitudinally extending suspensory members having chain links including longitudinally extending shank portions, a plurality of rungs including bars composed of wood, there being annular recesses in the ends of each of said bars, a metal ring positioned in each of said recesses to serve as a reinforcement against splitting the bar, a metal clip having side arms to engage the sides of each bar adjacent its end and also having a loop adjacent the end of each bar to receive a shank portion of an adjacent chain link, and means for securing the side arms of each clip to its wooden bar, and the bars being spaced along said longitudinally extending chains to form a plurality of adjacent ladders.

3. The combination of a plurality of longitudinally extending suspensory members having chain links including longitudinally extending shank portions, a plurality of rungs including rigid bars composed of a buoyant material, clips, each clip having a cylindrical portion to receive one end of a bar and having a loop adjacent each end of a bar, the loops receiving the shank portions of links of said longitudinally extending chains, and the bars being spaced along said longitudinally extending chains to form a plurality of adjacent ladders.

4. The combination of a plurality of parallel suspensory members having chain links including longitudinally extending shank portions, a plurality of rigid rungs, means for pivotally connecting the ends of the rungs spaced from one another to shank portions of adjacent chains to form a plurality of parallel ladders, said connecting means each including a metal clip having a loop formed adjacent the free end of a rung to receive a shank portion of a link of one of said suspensory members, and spacers connected to said chains to space the rungs from the side of a vessel or the like when in use, the rungs and spacers being composed of a buoyant material to cooperate with one another to facilitate retrieving the chain should it accidentally drop into the water.

5. The combination of a plurality of parallel chains, a plurality of rigid rungs, means for pivotally connecting the ends of the rungs spaced from one another to links of adjacent chains to form a plurality of parallel ladders, spacer blocks composed of a buoyant material and including two complementary semi-cylindrical portions having registering recesses to form a central opening to receive links of said chains, and means for anchoring the two complementary portions to one another in locking position with the chains, the spacer blocks being spaced from one another and distributed throughout the ladder effectively to space the ladder from the side of a vessel or the like.

6. The combination of a plurality of parallel chains, a plurality of rigid rungs, means for pivotally connecting the ends of the rungs spaced from one another to links of adjacent chains to form a plurality of parallel ladders, spacer blocks composed of wood and including two complementary semi-cylindrical portions having registering recesses to form central openings to receive links of said chains, and fastening means, each extending through the two portions and intercepted link of the adjacent chain to anchor the two complementary portions to one another to form a composite spacer block and to lock such

spacer block to the adjacent chain, the spacer blocks being spaced from one another and distributed throughout the ladder effectively to space the ladder from the side of a vessel or the like.

5 7. The combination of a plurality of longitudinally extending parallel chains, a plurality of rigid rungs and spacers, and means for connecting said rungs and spacers to links of said chains and spaced from one another to form a plurality of parallel ladders and effectively to space the ladders from the side of a vessel or the like, each spacer connected to a chain independent of any other spacer or chain and the connecting means between said rungs and chains being pivotal about a longitudinally extending axis.

10 8. The combination of a plurality of parallel suspensory members having chain links including longitudinally extending shank portions, a plurality of rigid rungs, metal clips having side arms connected to the sides of said rungs and looped portions adjacent the free ends of said rungs, and spacer disks having slits to receive said side arms and having flanges to engage the sides of said rungs adjacent their free ends, the looped portions receiving shank portions of adjacent chain links, said rungs being spaced from one another to form a plurality of parallel ladders and said disks being effective to space the ladders from the side of a vessel or the like.

15 9. The combination of a plurality of parallel chains, a plurality of rigid rungs, means for pivotally connecting the ends of the rungs to links of adjacent chains to form a plurality of adjacent parallel ladders, a border chain connected to the upper ends of said parallel chains to receive lashings for connecting the ladders to the rail of a vessel, a plurality of brackets each including an arm pivotally connected to the side of a vessel, a second arm having a securing hook at one end thereof, and a common bar forming the pivotal point for connecting said first and second arms to one another to also form an abutment for said ladders to space the same from the side of the vessel when in use.

20 40 10. The combination of a plurality of parallel chains, a plurality of rigid rungs, means for pivotally connecting said rungs spaced from one another to said chains to form a multiple ladder, such connecting means each including a metal clip having a loop formed adjacent the free end of a rung to receive a shank portion of a link of one of said longitudinally extending chains, and transversely extending form maintaining means loosely connected to said chains to maintain said ladder spread out ready for use when extended although movable laterally and axially relative to said chains to enable the ladder to orient its position relative to the structure with which it is being used.

25 60 11. The combination of a plurality of parallel chains, a plurality of rigid rungs, means for pivotally connecting said rungs to said chains spaced from one another to form a multiple chain ladder, booms extending the full width of the ladder, said connecting means each including a metal clip engaging the sides of a rung adjacent each end thereof, the clip also having a loop formed adjacent the free end of a rung to receive a shank portion of a link of one of said longitudinally extending chains, and means for movably connecting the booms to said chains spaced from one another to maintain said ladder spread out ready for use when extended.

70 75 12. The combination of a plurality of parallel chains, a plurality of rigid rungs, means for piv-

totally connecting said rungs to said chains spaced from one another to form a multiple chain ladder, booms extending the full width of the ladder, means for connecting one of said booms to the lower ends of said chains and the rest of said booms to said chains spaced from one another to maintain said ladder spread out ready for use when extended, lanyards connected to said lowermost boom, and floats on said lanyards to serve as rescue lines for users in case of an emergency.

13. The combination of a plurality of parallel chains, a plurality of rigid rungs, means for pivotally connecting said rungs to said chains spaced from one another to form a multiple chain ladder, booms extending the full width of the ladder, and means for connecting one of said booms to the lower ends of said chains and the rest of said booms to said chains spaced from one another to maintain said ladder spread out ready for use when extended, the free ends of said lowermost boom extending beyond the chains of said ladder, halyards connected at one of their ends to the deck of a vessel, and wrapped around the free ends of said lowermost booms, with their other ends free to be engaged by a user to roll up the ladder when it is to be stored out of use.

14. The combination of a plurality of parallel chains, a plurality of rigid rungs, means for pivotally connecting said rungs to said chains spaced from one another to form a multiple chain ladder, wood booms extending the full width of the ladder, means for connecting one of said booms to the lower ends of said chains and the rest of said booms to said chains spaced from one another to maintain said ladder spread out ready for use when extended, the free ends of said lowermost boom extending beyond the chains of said ladder, and halyards connected to the free ends of said lowermost boom with ends thereof free to be engaged by a user to pack up the ladder when it is stored out of use.

15. The combination of a plurality of parallel chains, a plurality of rigid rungs, means for pivotally connecting said rungs to said chains spaced from one another to form a multiple chain ladder, wood booms extending the full width of the ladder, means for connecting one of said booms to the lower ends of said chains and the rest of said booms to said chains spaced from one another to maintain said ladder spread out ready for use when extended, the free ends of said lowermost boom extending beyond the chains of said ladder, halyards connected to the free ends of said lowermost boom with ends thereof free to be engaged by a user to pack up the ladder when it is stored out of use, and links spaced from one another at intervals along the outermost chains of said ladder to receive halyards and serve as guides for the same when raising or lowering said lowermost boom in turn to pack up the ladder when it is stored out of use and in turn to lower it into use.

16. The combination of parallel flexible longitudinally extending suspensory members having chain links including longitudinally extending shank members, a plurality of rigid rungs composed of a buoyant material, and metal clips secured to said rungs and forming connecting means at the ends of said rungs each clip having a loop to receive a longitudinally extending shank portion of a link to form a pivotal connection between such rung and a suspensory member, said

rungs being spaced from one another to form a ladder.

17. The combination of a plurality of parallel flexible longitudinally extending suspensory members having chain links including longitudinally extending shank members, a plurality of rigid rungs composed of a buoyant material, clips secured to said rungs and forming connecting means at the ends of said rungs each clip having a loop to receive a longitudinally extending shank portion of a link to form a pivotal connection between such rung and suspensory member, said rungs being spaced from one another between each two suspensory members to form a multiple ladder, and rigid booms extending along the rear side of, and movably connected to, said suspensory members to space the ladder from the side of the structure along which it is suspended and to maintain the ladder spread apart although movable laterally and axially relative to said booms to orient the position of the ladder relative to the structure with which it is being used without concentrating the shearing forces on the connection between the booms and the suspensory members.

18. The combination of a plurality of parallel flexible longitudinally extending suspensory members having chain links including longitudinally extending shank members, a plurality of rigid rungs composed of a buoyant material, and clips secured to said rungs and forming connecting means at the ends of said rungs each having a loop to receive a longitudinally extending shank portion of a link to form a pivotal connection between such rung and a suspensory member, said rungs being spaced from one another between each two suspensory members to form a multiple ladder, the rungs between each two adjacent parallel suspensory members forming a set, with the rungs of each set staggered relative to the rungs in either adjacent set to enable the rungs in adjacent sets exclusively to be secured to any link.

19. The combination of a plurality of parallel longitudinally extending flexible suspensory members, a plurality of rigid rungs, clips secured to the ends of said rungs and forming pivotal connections between the ends of said rungs and said members, said rungs being spaced from one another between each two suspensory members to form a multiple ladder, means for movably connecting the upper ends of said suspensory members to the structure with which said ladder is to be used, and a rigid boom movably connected to said suspensory members to maintain the ladder spread apart although movable laterally and axially relative to said boom.

20. The combination of a plurality of parallel chains, a plurality of rigid rungs, means connecting said rungs spaced from one another to said chains to form a multiple ladder, such connecting means each including a metal clip having a loop formed adjacent the free end of a rung and connected to a link of one of said longitudinally extending chains, and transversely extending form maintaining means loosely connected to said chains to maintain said ladder spread out ready for use when extended although movable laterally and axially relative to said chains to enable the ladder to orient its position relative to the structure with which it is being used.

NOËL L. DAHLANDER.
